FLAT KNITTING MACHINE

Karl Willi Lieberknecht, Oberlungwitz, Germany,
assignor to Kallio Inc., New York, N. Y., a corporation of New York

Application January 24, 1933, Serial No. 653,270
In Germany February 19, 1932

4 Claims. (Cl. 66—114)

Flat knitting machines designed for use with spring beard needles are sometimes provided with a needle bar divided into sections, the central section being swingable or otherwise removable from knitting position in order that the knitting of certain parts of the fabric can be suspended without removing the fabric from the needles of that section while the knitting of other portions is performed on the other sections. For example, in knitting single unit stockings, a needle bar of this kind is sometimes employed in which the section of the needle bar which carries the needles which knit the instep may be removed from knitting position as above described, the object being to retain the instep portion upon the needles while the heel tabs are knit upon adjacent sections of the needle bar so that at the proper time the instep can be brought back into knitting position simply by swinging the movable section of the needle bar back into knitting position.

A sectional needle bar of this character having a central section which is swingable out of knitting position is described, for example, in Patent No. 1,901,757 issued to Karl Richard Lieberknecht. While a needle bar of this character possesses several advantages, it also has one drawback, namely, that while the heel tabs are being knit the previously knit loops of the instep portion are hanging on the needles and are supported by the knockover bits. Since the needles have been swung out of their normal position, a greater tension than normal is imposed upon the loops and they are continually struck by the knockover bits, with the result that they are apt to be distorted and enlarged and even broken, all of which, of course, is objectionable and detrimental to the production of high grade fabric.

By this invention I retain the desirable features of the sectional needle bar and eliminate the undesirable ones, and I accomplish these ends in an extremely simple manner which leaves practically no danger of improper operation and consequently imperfect knitting.

The nature of my invention is described in the following specification and illustrated in the accompanying drawing, of which

Figure 1 is a front elevation of the needle bar of my invention;

Fig. 2 is a cross-section thereof along the line A—A of Figure 1; and

Fig. 3 is a fragmentary view of a detail modification of Fig. 2;

Fig. 4 is a similar cross-section showing the

action of the central section of the needle bar at the time of press during the knitting of the heel tabs.

For the sake of simplicity, I have confined the following description to a hosiery machine. It will be understood, however, that the invention is applicable to any flat knitting machine and the knitting of any fabric thereon in which the knitting of certain sections is suspended during the knitting of others.

The needle bar is composed of a main section 1 and a movable central section 3. The needles which are employed in knitting the instep are carried upon movable section 3 and the remaining needles upon the main section 1. The central section 3 is pivoted to the needle bar support as at 2, so that it may swing forward. Normally, the needles of central section 3 are in alignment with the rest of the needles. They may be held in that position by means of a suitable latch consisting, for example, of a spring pressed bolt 5 on the main needle bar 1, which engages with a surface 11^a on the central section 3. Preferably, the engaging surfaces of this latch are beveled, as shown, so that the bolt will have a tendency to urge the central section of the needle bar backward and maintain it in alignment. Irrespective of the bolt, however, I provide other means which will tend to maintain the central section 3 of the needle bar in alignment with the other sections, but which at the same time will permit it to swing out of alignment at certain times. This consists of spring 6, one end of which is attached to an arm 7 on central section 3 and the other end of which is attached to some stationary part of the machine such as the needle bar support 8.

If bolt 5 is disengaged from central section 3, this section will still be urged backwardly and into alignment with the other sections through the action of spring 6. However, if the needles of central section 3 are opposed by any force greater than that of spring 6, central section 3 of the needle bar will swing forward as long as this force exists, but will again return to its normal position as soon as the force is removed.

As already stated, the object of such a sectional needle bar is the retention of certain loops, such as the instep loops upon the needles during the knitting of other parts such as the heel tabs; that is to say, the instep loops are not cast off. This is accomplished by preventing the beards of the needles from being pressed. This may be effected by swinging the central section of the needle bar out of knitting position as

- already described. It may be accomplished to better effect by the device of this invention. When the time comes for suspending the knitting of the instep portion during the knitting 5 of the heel tabs, bolt 5 is withdrawn, unlocking the central section of the needle bar. When the needle bar is rocked backward to bring the beards of the needles against the presser edge, the needles of the central section will rock with those 10 of the other sections and will engage with the presser edge. However, the strength of spring 6 is less than the combined resistance of the beards of the needles of central section 3, so that when these needles strike the presser edge 15 their beards will not be closed. Instead, the entire central section will remain substantially stationary while the remainder of the needles go to press, the central section simply rocking upon its pivots 3.
- 20 When the pressing off of the loops from the other needles is completed and the needle bar reassumes its normal position, the needles of the central section again align themselves with the others. Thus, the loops upon the needles of 25 the central section are retained without stretching or distorting them to any appreciable extent and, consequently, without subjecting them to any undue strain through contact with the knock-over bits when under abnormal tension. When 30 all of the needles of all the sections are required to knit in unison in the normal way, the central section may be locked by the latch already described so that the entire needle bar becomes a single operating unit.
- 35 Some means will, of course, be provided for insuring that the central section of the needle bar when swung back will be in alignment with the other sections of the bar. This may be a set screw 9 passing through central section 3 and 40 engaging the main needle bar. By screwing this set screw in or out the alignment of the needles of section 3 may be varied.
- 45 It will be understood, of course, that spring 6 may be replaced by a counterweight or any other suitable device for maintaining the desired tension upon central section 3. Such a counterweight is shown at 6^a in Fig. 3.
- Bolt 5 may be operated as above described by 50 any suitable means such, for example, as that shown and described in the patent of Karl Richard Lieberknecht, No. 1,899,577, which also relates to a sectional needle bar. As shown therein and in the drawing hereof, bolt 5 may be provided with a pin 10 adapted to engage with a rod 11 55 mounted so as to be longitudinally slidable in brackets 12 on the main needle bar 1. Rod 11 is provided with an upwardly curving cam surface 12^a adapted to engage with pin 10. When the highest portion of this cam surface is in engagement with pin 10, the bolt will be urged upwardly 60 into engagement with the central section 3 of the needle bar by its spring. When the rod is laterally shifted, pin 10 will be forced downwardly, carrying bolt 5 with it and the central section of 65 the needle bar will be unlocked. The shifting of rod 11 may be accomplished by any desired means—mechanical or manual—that shown being a hand shaft 14 connected to rod 11 by arms 13. Longitudinal movement of shaft 12 will effect 70 the corresponding movement of rod 11.
- By this invention I have retained the advantages and overcome the disadvantages of the sectional needle bar having a section which is swung and maintained out of knitting position, and at the same time I have also avoided the use of any devices which will prevent certain needles from going to press during the pressing of the rest of the needles by springing them out of alignment, which puts abnormal strains on them.
- In short, no appreciable strain is put upon either the fabric or the machine of my invention, since all of the needles remain in alignment all of the time with the exception of when the needles of the central section are swung slightly out of alignment, when they contact with the presser 10 edge. This and the fact that I accomplish my objects through an extremely simple structure is a matter of great practical importance, both to the manufacturer and user of the knitting machine.
- 15 What I desire to seek by United States Letters Patent is:
1. In a flat knitting machine having a presser bar, a needle bar supporting spring beard needles and having a section thereof which is swingable out of knitting position, means for maintaining said swingable section in an aligned position with the other sections of the needle bar, means for retracting said last mentioned means to release said swingable section from its aligned position, and 20 additional means to maintain said swingable section in an aligned position with respect to the other sections of the needle bar in such a manner when said first-mentioned maintaining means is retracted, that the beards of the needles 25 thereof will not close when the needles of all the needle bar sections are pressed against the presser bar in a knitting operation of the machine but will realign themselves with the beards of the other needles when the pressing off operation 30 with respect to the other needles is completed.
  2. A flat knitting machine having a needle bar one section of which is movable out of alignment with the other sections, means for maintaining said movable section in aligned position, means for retracting said last mentioned means, and means comprising a spring for maintaining the needles of the swingable section in alignment with the other sections when the first mentioned alignment maintaining means is retracted, said spring 40 having a resilient strength less than the combined resistance of the beards of the needles of the movable section so that when the needles of all the needle bar sections are pressed against the presser bar in a knitting operation of the machine, the beards of the needles of the movable section will not close and will be positioned out of alignment with the beards of the needles of the other section.
  3. In a flat knitting machine having a presser bar, a sectional needle bar supporting spring 55 beard needles and having one section thereof capable of movement so that needles thereof may be moved out of alignment with the needles of other sections, means to maintain said movable section normally in alignment with the other sections of the needle bar, and additional means associated with the movable section to resiliently maintain it in an aligned position with respect to the other sections in such a manner that at predetermined times when the normal aligning maintaining means is retracted, the movable section will be forced out of alignment with the other sections, as the needles of all the sections are pressed against the presser bar in a knitting operation of the machine to such an extent that the beards of the needles of the movable section will not be closed by said pressing operation.
  4. In a flat knitting machine, having a presser bar, a sectional needle bar supporting spring beard needles and having one section thereof ca- 70

5
pable of movement out of alignment with the other sections, means for adjusting the alignment of said movable section with the other sections of the needle bar, means to maintain said movable section in any adjusted position, means for retracting said last mentioned means to release said movable section from its aligned position, and additional means associated with the movable section to resiliently maintain it in aligned

position with respect to the other sections when the first mentioned alignment maintaining means is retracted and so that when the needles of all the sections are pressed against the presser bar the movable section will be forced out of alignment with the other sections to such an extent that the beards of the needles of the movable section will not be closed by this pressing operation.

KARL WILLI LIEBERKNECHT.
